CLAIM

The ornamental design of a bumper and towing receiver for vehicles, as shown and described.

DESCRIPTION

FIG. 1 is a perspective, upper front corner view of a bumper and towing receiver installed on a tracked firefighting vehicle.

FIG. 2 is an elevated front view of the bumper and towing receiver of FIG. 1.

FIG. 3 is an elevated rear view thereof.

FIG. 4 is a top view thereof.

FIG. 5 is a bottom view thereof.

FIG. 6 is an elevated left view thereof; no right view is provided as it is a mirror-image of the left view; and,

FIG. 7 is perspective, upper-rear corner view thereof.

The broken lines represent portions of the bumper and towing receiver for vehicles that form no part of the claimed design.
